UNITED STATES PATENT OFFICE.

LEANDER SPAULDING, OF NORFOLK, VIRGINIA.

IMPROVEMENT IN DEVICES FOR TAPPING MAINS.

Specification forming part of Letters Patent No. **147,700**, dated February 17, 1874; application filed July 17, 1873.

To all whom it may concern:

Be it known that I, LEANDER SPAULDING, of Norfolk, in the county of Norfolk and State of Virginia, have invented an Improved Machine for Tapping Mains; and I do hereby declare the following to be a full and exact description of the same, reference being had to the accompanying drawings forming part of this specification, in which—

Figure 1 is a perspective view of the tapping apparatus applied to a main. Fig. 2 is a transverse vertical section of the same. Fig. 3 is a sectional elevation of the permanent fitting and its operating-stem, and Fig. 4 is a sectional plan of the spring-ratchet for turning the tap.

Similar letters of reference in the accompanying drawings denote the same parts.

The object of this invention is to facilitate the tapping of gas, water, and steam pipes. To this end the invention consists in the construction and combination of parts, which I will now proceed to explain.

In the accompanying drawing, A represents the pipe to be tapped. Preliminary to the operation, I place on the pipe a saddle, B, constructed for the purpose, the same having lugs B' projecting one from each side, said lugs having holes in them, through which pass the ends of a yoke, C, that goes around that part of the pipe not covered by the saddle B, and is connected with said saddle by means of keys D, driven through slots in the ends of the yoke above the lugs B', thus fastening the saddle securely to the pipe, a packing having been placed beneath the saddle to prevent leakage when the pipe is first tapped. The saddle B has a tapped sleeve, E, extending from its convex side, into which sleeve is screwed a tube, F, which has a tubular branch, F', at one side, closed by a removable plug, G. In this branch is a disk-valve, G¹, which is of a size to close the tube F, and has a stem, G², extending outside the branch F', by which to work said valve from the outside. H is the tap, which is put into the tube F and branch E, and is centered therein by guides O on the inside of the branch, as shown in Fig. 2, and also by means of a stuffing-box, H', screwed

on the top of the tube F. This tap has a square head, on which is fitted the ratchet. A yoke, I, goes on the outside of the tube F, below the box H', which yoke carries a set-screw, I', that bears on the head of the tap during the tapping operation. This set-screw has a square foot, on which is a collar, J. On the top of the upper plate K of the ratchet is pivoted a button, L, with a handle, L'. When this button is turned between the ratchet and the collar J, the tap and set-screw are not cooperative; but, when it is desired to force the tap into the main, the button L is turned back, and this allows the collar J to drop upon the square head of the tap, as shown in Fig. 1, and, consequently, when the tap is turned the set-screw is turned with it, and follows it down, exerting a continual pressure upon it. The ratchet has a double pawl, J', which is pressed upon by a bolt, J², and spring, J³, in the handle K', and hence is operative to turn the tap in either direction.

When the main is to be tapped, the parts above described being arranged as shown in Figs. 1 and 2, the tap is set in motion by means of the handle K', and run down into the main. After the main is tapped to the proper depth, the button L should be thrust between the ratchet and collar J, so as to lift the latter from the tap. Then, by running up the set-screw, the yoke is loosened, and can be tipped to one side and the tap drawn up into the tube F. Then the valve G¹ is to be turned across the tube F, and the pressure of the liquid flowing from the main through the hole just made therein keeps the valve closed.

Having described my invention, what I claim is—

1. The combination of the tube F, guide O, valve G¹, screw-plug G, and stem G², all constructed, arranged, and operated as set forth.

2. The combination of the set-screw I' and tap H, provided with square heads, ratchet K, collar J, and the adjustable button L, substantially as and for the purpose specified.

LEANDER SPAULDING.
